(74) Attorney, Agent, or Firm — Swanson & Bratschun,
L.L.C.(57) **CLAIM**

The ornamental design for a three-wheeled vehicle, as shown and described.

DESCRIPTION

FIG. 1 is a top, front, and right side perspective view of a three-wheeled vehicle showing my new design;

FIG. 2 is a top, front, and left side perspective view thereof;

FIG. 3 is a front elevation view thereof;

FIG. 4 is a left side elevation view thereof;

FIG. 5 is a right side elevation view thereof; and,

FIG. 6 is a top plan view thereof.

The broken lines in the drawings illustrate portions of the three-wheeled vehicle that form no part of the claimed design.
